CLAIM

The ornamental design for medical solution bag, substantially as shown and described.

DESCRIPTION

FIG. 1 is an elevational view of a medical solution bag, showing my new design.

FIG. 2 is a top plan view of the bag of FIG. 1.

FIG. 3 is an elevational view of the bag of FIG. 1 but rotated 90° about its longitudinal axis from the view of FIG. 1.

FIG. 4 is a bottom plan view of the bag of FIG. 1.

Fig.1.

Fig.2.

Fig. 4.
